(57) **CLAIM**

The ornamental design for a sensor for water-conducting appliances, as shown and described.

DESCRIPTION

FIG. 1 is a top front left perspective view of a sensor for water-conducting appliances according to the invention;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a bottom, rear, right perspective view thereof;

FIG. 9 is a partial top, front, left perspective view of the sensor portion of the sensor for water-conducting appliances; and,

FIG. 10 is a partial bottom, rear, right perspective view of the sensor portion.
